UNITED STATES PATENT OFFICE.

WILLIAM ZEEDYK, OF PATERSON, NEW JERSEY, ASSIGNOR TO BENJAMIN EASTWOOD COMPANY, OF PATERSON, NEW JERSEY, A CORPORATION OF NEW JERSEY.

LOOM.

Application filed September 28, 1920. Serial No. 413,321.

To all whom it may concern:

Be it known that I, WILLIAM ZEEDYK, a citizen of the United States, residing at Paterson, in the county of Passaic and State 5 of New Jersey, have invented certain new and useful Improvements in Looms, of which the following is a specification.

This invention relates to looms, and particularly to shuttle impelling means for 10 looms of the class in which the shuttle-impelling or picking member is spring-pressed and is alternately cocked and released. The invention consists in certain improvements in shuttle-impelling means which have been 15 already disclosed (but not claimed) in an application filed by one William S. Wells, Serial No. 343,599, and hereinafter set forth in the claims appended to this specification.

In the accompanying drawings, 20 Figure 1 is a side elevation of a loom embodying my invention;

Figure 2 is a section on line 2—2, Figure 1; Figures 3 and 4 are a side elevation and a plan, on a larger scale, of certain parts 25 appearing in Figures 1 and 2;

Figures 5 and 6 are front and side elevations of the picker stick mounting or carrier; and

Figures 7 and 8 are views illustrating the 30 means for automatically cutting out the shuttle impelling operation when the loom stopping means is operated.

The loom side *a*, the crank shaft *b* journaled therein, the rock-shaft *c* on which the 35 lay-swords *d* for the lay or batten *e* are fixed, the pitman *f* connecting the crank-shaft with the lay or batten structure (*c, d, e*) and the hand-wheel *g* for turning the crank shaft *b* manually are or may be all 40 the same as in ordinary looms.

The means now to be described, except as indicated, will be duplicated in the loom, one at one side and the other at the other, being adapted to act in alternation, as will 45 be understood, so as to throw the shuttle back and forth.

A bracket generally designated by the character *k* and including a sleeve *k'* and a forward upstanding arm *k''*, has its sleeve fitted 50 over and secured to the projecting end of the shaft *c* by screws *l* (Figures 3 and 4); this bracket may also include the member *k''* suitably secured to its under side and having a rearwardly projecting web *k'''* formed 55 with an elongated upstanding outwardly

projecting arm *k''''* and an inwardly projecting arm *k'''''*. On a stud *k''''* projecting from arm *k''''* rearwardly of the same is fulcrumed a lever forming the carrier or mounting for the picker stick, the same being designated 60 *m* in Figures 1 and 3 and shown in Figures 5 and 6 as including a hub *m'* journaled on stud *k''''*, a downwardly projecting arm *m''* having a hardened plate *m''''* secured thereto and projecting downwardly therefrom to form 65 a shoulder *m''''*, an inwardly projecting arm *m'''''* and an upwardly projecting arm *m''''''*; a U-shaped clip *m''''''* receives between its branches the arm *m''''* and is pivoted therein on the stud *m''''*, and above the clip there is 70 suitably secured to arm *m''''* a loop *m''''''* preferably of leather. The picker stick *n* is embraced by the loop *m''''''* loosely and is received and secured by a bolt *o* in and to the clip *m''''''*, so that the stick is freely movable with the 75 clip on its fulcrum *m''''* from a position of contact with arm *m''''* to such a limit outwardly of the arm as the loop *m''''''* permits.

On a stud *p* in the outer end of arm *k''''* is fulcrumed a cocking shoe *q* having secured 80 to its under side near its fulcrum a plate-spring *r* which rests on the web *k''''* and which, when the picking member *m* is swung to the position shown in Figure 3, is adapted 85 by the projecting plate *m''''* thereof to be depressed and then catch and hold said member in said position, or cocked, the shoe having a hardened cocking shoulder *s* to receive the contact of the shoulder *m''''* at that time; the upward movement of shoe *q* may 90 be limited by a set-screw *q'*. It will be understood that the picker-stick *n* plays in a suitable slot *t* (Figure 1) in the batten *e* and that it will be equipped with a picker (not shown). The inward movement of 95 each picking member may be limited by a suitable buffer, as *u* in Figure 1.

A spring 25 of the laminated plate type for urging the picking member inwardly is arranged on a stud 26 on a bracket attached 100 to the side of the loom, the spring projecting forwardly and having its end arranged to pull downwardly on the arm *m''''* of the picking member through the medium of a universal-joint connection or link 27 and 105 having means, as a set screw 28, for adjusting the pressure thereof.

The cocking and tripping of the picking members is accomplished by a master lever 110 29 for each picking member, the same being

fulcrumed on the frame side *a* and having its forward end projecting between the roller 30 (on a stud 31 which projects from link 27) and the corresponding cocking shoe, there preferably being a set-screw 32 in said lever to impinge against the shoe. When the lever is oscillated it will alternately cock the corresponding picking member, by impinging against roller 30 as it rises, and trip it, by depressing the shoe *q* as it descends, preferably through the medium of a device 41 to be described.

A buffer 25' is provided to receive the downward impact of spring 25 when lever 15 29 depresses the cocking shoe and so releases the picking member; otherwise such impact would be assumed by the cocking shoe.

The movements of the two levers 29 of the two picking mechanisms (one at each side 20 of the loom) in proper time are effected from sprocket wheels 33, which have endless chains 34 extending around them and sprocket-wheels 35 on shaft *b*, through pitmen 36 connecting eccentric points of 25 sprocket-wheels 33 with the levers; only one of each of the parts 33 to 36 is shown.

I have illustrated means for preventing tripping of the picking members and therefore cutting out their operation when the 30 means for stopping shaft *b* and hence the loom is operated. Thus, 37 indicates a part of the means for stopping the loom (which means may be of any well known type) being here a lever at one side of the loom which, when thrown to the dotted position in Figure 1, to stop the loom, depresses a rod 38 which rocks a fork-lever 39 fulcrumed in the side frame, said fork-lever in turn shifting a lever 40, fulcrumed on arm *h*^{6*}, from between the lever 29 and the cocking shoe; lever 40 has a spring elevated button 41 for transmitting the downward pressure of lever 29 to the cocking shoe, and when said lever 40 is shifted to the dotted 45 position (Figure 8) lever 29 will fail to depress the cocking shoe, so that the picking member remains cocked. The two levers 40 (one at each side of the loom) may be connected (Figure 7) so as both to be shifted 50 and thus cut out both tripping members at the same time by the link 42. When the loom is turned over by hand there is a possibility of the shuttle leaving the lay and missing the box, on account of the forward 55 movement of the lay being then too slow to keep the advancing lay against the shuttle should it tend for any reason to veer forward in its flight, and this creates an element of danger, especially since the shuttle 60 travels at much greater velocity than in the ordinary case where it is impelled by tap-pet means. The advantage of cutting out the action of the picking means when the loom-stopping means is operated will therefore be apparent.

The invention is shown applied to a loom of the type in which the picking member partakes of the back-and-forth or rocking motion of the batten-including structure. It considerably simplifies the mechanism 70 and renders the same more substantial and durable and also accessible and more easily adapted to an already existing loom to mount the principal actuators 25 and 29 on the loom frame. 75

So far as I am aware it is new in this art to provide in a suitable supporting structure (as the frame and the batten-including structure in the present example) a cockable train including a back-and-forth movable picking member and a spring normally urging said member in one direction for impelling the shuttle, a movable cocking device normally held in position to dog said train and hold the latter cocked when moved in the other direction, and an actuating member movable in the supporting structure in one direction against said train to move the same to cocking position and in the other direction against the cocking device to move the latter clear of said train. 85

It is also new to provide, in combination, with a supporting structure and the going driving member (as *b*) and stopping means (as 37) therefor of a loom, a cockable 90 spring-pressed picking member, a cocking shoe *q* or equivalent for said member, a train of elements (as 35, 34, 33, 36, 29, 32 and 40) actuated by the driving member and adapted to move the shoe or equivalent 100 whereby to release the cocked picking member, one element of said train being withdrawable therefrom, and operative connecting means (as 40, 39 and 38) between said element and the stopping means, whereby to control the release of the picking member. 105

Having thus fully described my invention, what I claim as new and desire to secure by Letters Patent is: 110

1. In combination, a supporting structure having a fixed portion and a batten-including portion movable back and forth, a cockable picking member movable with and also back and forth in the movable portion of 115 said structure, a plate-spring fixed in the fixed portion of said structure and normally urging said member in the direction for impelling the shuttle, a cocking device to hold said member cocked against the tension of said spring and movable to release the same, and means to move said member to cocking position and said device to position to release said member in alternation. 120

2. In combination, a supporting structure 125 having a fixed portion and a batten-including portion movable back and forth, a cockable picking member movable with and also back and forth in the movable portion of said structure, a plate-spring fixed in the 130

fixed portion of said structure and normally urging said member in the direction for impelling the shuttle, a cocking device in the movable portion of said structure to hold 5 said member cocked against the tension of said spring and movable to release the same, and means to move said member to cocking position and said device to position to release said member in alternation.

10 3. In combination, with a loom frame, a forward - and - back movable structure arranged therein, a picking member movable with and also back and forth in the movable structure and having a laterally projecting 15 arm, a spring member fixed in the frame and confined to move in an approximately vertical plane and exerting pressure substantially vertically on said arm and thereby urging said member in the direction for impelling the shuttle, and means to move said member in the contrary direction preparatory to the impelling of the shuttle.

4. In combination, with a supporting structure, cockable means including a picking member movable back and forth in said structure and a spring normally urging said means in the direction for impelling the shuttle, a cocking device movable in said structure and normally held in position to 30 engage said means and hold the latter cocked when moved in the other direction, and an actuating member movable in said structure in one direction against said means to move the same to cocking position and in the other 35 direction against the cocking device to move the latter clear of said means.

5. In combination, with a supporting structure, cockable means including a picking member having a lateral arm and moving 40 able back and forth in an upright plane and a spring normally urging said means in the direction for impelling the shuttle, a cock-

ing device movable in said structure in an upright plane and normally held in position to engage said means and hold the latter 45 cocked when moved in the other direction, said device and arm being arranged one above the other, and means movable back and forth into engagement with said arm and device alternately to alternately move 50 the first-named means to cocking position and the cocking device clear of said first-named means.

6. In combination, with a frame and a forward-and-back movable structure therein, a cockable means including a picking member movable back and forth in said structure and a spring secured to the frame and normally urging said member in the direction for impelling the shuttle, a cocking device movable in said structure and normally held in position to engage said means and hold the latter cocked when said member is moved in the other direction, and an actuating member movable in the frame 65 in one direction against said means to move the same to cocking position and in the other direction against the cocking device to move the latter clear of said means.

7. In combination, with a supporting 70 structure and the rotating driving member and stopping means therefor of a loom, a cockable spring-pressed picking member movable in said structure, means to hold said picking member in cocked position movable to release the same, a train of elements actuated by the driving member and adapted to move the second means whereby to release the cocked picking member, one element of said train being withdrawable therefrom, and operative connecting means between said element and the stopping means.

In testimony whereof I affix my signature.

WILLIAM ZEEDYK.
